(57) **CLAIM**

The ornamental design for a billiard table frame, substantially as shown and described.

DESCRIPTION

FIG. 1 is a perspective view of a billiard table having the new frame design;

FIG. 2 is a top plan view of the billiard table shown in FIG. 1;

FIG. 3 is a side elevational view of the billiard table and frame shown in FIG. 1;

FIG. 4 is an end elevational view of the billiard table and frame shown in FIG. 1;

FIG. 5 is a bottom view of the billiard table and frame shown in FIG. 1; and,

FIG. 6 is a perspective view of a portion of the frame shown in FIG. 1 illustrating contours thereof.
